UNITED STATES PATENT OFFICE.

FREDERICK J. LEE, OF OSWEGO, KANSAS.

DOOR.

SPECIFICATION forming part of Letters Patent No. 309,633, dated December 23, 1884.

Application filed May 22, 1884. (No model.)

To all whom it may concern:

Be it known that I, FREDERICK J. LEE, of Oswego, in the county of La Bette and State of Kansas, have invented certain new and useful Improvements in Doors; and I do hereby declare that the following is a full, clear, and exact description thereof, reference being had to the accompanying drawings, and to the letters of reference marked thereon, which 10 form part of this specification.

The object I have specifically in view is to provide or construct a door which, though closed and locked, may be interchangeably used, either for the ordinary purpose of security or for ventilation, and which, at the same time, will prevent the entrance of insects; and to these ends my invention consists in the combination, with a door-frame, of a sliding panel and a wire-gauze screen arranged as 20 will be hereinafter more particularly described and understood when taken in connection with the annexed drawings, in which—

Figure 1 is a front elevation of the door with the panel raised for security; Fig. 2, a 25 similar view with the panel lowered for ventilation; and Fig. 3, a transverse section on line $x-x$, Fig. 1.

Similar letters of reference denote like parts.

A represents an ordinary door-frame having the usual lower fixed panel, B.

C represents a sliding panel, which, when elevated, as seen in Fig. 1, forms a sealed or closed door, but when lowered, as seen in Fig. 2, the portion above the lower panel is open.

35 D indicates a wire screen, which is permanently and suitably secured to the door-frame,

above the stationary panel, so as to entirely extend over the open space left in the door when the sliding panel is lowered.

It will be seen that at night, or in case of a 40 storm, the movable panel may be closed and suitably secured by a bolt or hook. When it is warm and it is desirable to have ventilation, this panel may be lowered, thus exposing the wire screen, which will freely admit air but 45 prevent insects from entering the room.

I am well aware that wire screens have been employed in connection with sliding window-sash, and limit my claim to the obvious scope of my invention. 50

I am also aware that doors have been constructed with double stationary lower panels and a stationary hollow cross-bar in combination with a sliding panel adapted to close the space above the same; but such a contrivance I 55 disclaim.

What I claim, therefore, as new is—

The combination, with the door-frame provided with suitable guides, of a single stationary lower panel, a vertically-sliding panel 6c adapted to close the space above the said stationary panel, and a stationary wire screen located above this stationary panel, all constructed and adapted to operate as specified.

In testimony that I claim the foregoing as 65 my own I affix my signature in presence of two witnesses.

FREDERICK J. LEE.
